United States Patent Office

Des. 185,695
Patented July 21, 1959

185,695

CAN PUNCH

Norman Blumberg, Cleveland Heights, Ohio

Application February 27, 1959, Serial No. 54,764

Term of patent 14 years

(Cl. D44—29)

Fig. 1

Fig. 2

Fig. 3

Fig. 4

Fig. 1 is a top plan view of a can punch, embodying my new design;

Fig. 2 is a side elevation of the can punch;

Fig. 3 is a front elevation of the can punch; and

Fig. 4 is a rear elevation of the can punch.

I claim:

The ornamental design for a can punch, substantially as shown.
